UNITED STATES PATENT OFFICE.

STANLEY FRITZ AND ALEXANDER FRITZ, OF MANAYUNK, PHILADELPHIA,
PENNSYLVANIA.

VENTILATED HAT.

Application filed August 2, 1924. Serial No. 729,775.

To all whom it may concern:

Be it known that we, STANLEY FRITZ and ALEXANDER FRITZ, citizens of the United States, residing at Manayunk, Philadelphia, in the county of Philadelphia and State of Pennsylvania, have invented certain new and useful Improvements in Ventilated Hats; and we do declare the following to be a full, clear, and exact description of the invention, such as will enable others skilled in the art to which it appertains to make and use the same.

Our invention relates to improvements in hats of the type in which the wall of the crown is provided with an openwork portion for ventilating purposes, and one object of the invention is to provide a sliding band within the hat constructed and mounted in a novel manner to cover all or a part of the openwork portion of the crown wall, whenever desired, for instance, to prevent rain or a cold wind from driving through the openwork.

Another object of the invention is to provide a device of the class set forth which may be easily and inexpensively manufactured and hence sold at a reasonable price, at the same time providing an article which will present a neat and attractive appearance.

With the foregoing in view, the invention resides in the novel subject matter herein-after described and claimed, the description being supplemented by the accompanying drawing.

Figure 1 is a side elevation.

Figure 2 is a vertical longitudinal sectional view.

Figure 3 is a vertical transverse section on line 3-3 of Fig. 2, the slidable band being shown in raised position.

Figure 4 is a view similar to Fig. 3 but illustrating the slidable band in its lowered operative position.

Figure 5 is a vertical transverse sectional view on line 5-5 of Fig. 2 showing the slidable band raised.

Figure 6 is an enlarged view similar to a portion of Fig. 2, illustrating the slidable band in lowered position.

Figure 7 is a vertical sectional view on line 7-7 of Fig. 6.

Figures 8 and 9 are detail horizontal sections on lines 8-8 and 9-9 of Fig. 7.

In the drawing above briefly described,

the numeral 1 designates a rim of straw, felt or any other desired material, the inner edge of said rim having an upstanding flange 2. Spaced above this flange, is the wall 3 of a main crown section 4, also formed of straw, felt or any other preferred material. An openwork band 5 surrounds the flange 2 and the lower edge portion of the crown wall 3 and co-operates with the crown section 4 in forming a complete crown for the hat. The openwork band 5 may be formed of fabric, metal or other desired material, but finely woven wire is preferably used. The upper and lower edges of the band 5 may be secured to the crown wall 3 and the flange 2 in any desired manner, for instance by stitching as indicated at 6, and narrow hat bands 7 extend around the edge portions of the band 5 to obscure them, said bands 7 being of ribbon, elastic or any other suitable material.

Extending vertically between the flange 2 and the crown wall 3, are a number of substantially rigid guides 8 which are preferably of channel form with their edge walls turned inwardly toward each other as indicated at 9. These guides are secured in any desired manner to the flange 2 and the wall 3 and they serve to support the upper crown section 4 from the rim 1, taking strain from the openwork band 5. Vertical plates 10 are slidably received in the guides 8 and are preferably provided at their upper ends with inwardly extending ears 11 by means of which they may be readily raised or lowered, and to hold such slides in either raised or lowered positions, the guides 8 are preferably provided with upper and lower shallow recesses 12 and 13, and the slides are formed with rounded projections 14, adapted to snap into either the upper or lower recesses, as will be clear by comparing Figs. 5 and 7. A vertically movable band 15 is suitably connected with the slides 10 to be either raised into the crown of the hat as shown in Fig. 3, or to be lowered to prevent rain or cold air from entering the hat through the openwork band 5, as seen in Fig. 4. This band 15 is preferably formed of leather or other flexible material and has its upper and lower edges secured to a pair of wire rings 16 which are in turn secured to the slides 10, said edges of the band 15 being preferably turned around the wire rings 16 as shown at 17.

It will be seen from the above, that the guides 8 hold the upper crown section 4 and the rim 1 in rigidly spaced relation, as well as acting as guides for the slides 10.

5 Furthermore, in addition to serving merely as carriers and adjusters for the band 15, it will be seen that the slides 10 co-act with the rings 16 in retaining said band 15 in proper shape even though it may be formed 10 of leather or other flexible material.

The hat is provided with an appropriate sweat-band 18 which is of a type normally spaced inwardly to some extent from the wall of the crown, so that when the band 15 is lowered, the sweat-band will remain 15 at its inner side, as seen in Fig. 4.

It will be seen from the above that a very simple and inexpensive ventilated hat has been provided, yet one which will be very 20 desirable. In order to permit the circulation of air through the openwork band 5, it is simply necessary to move the band 15 to the raised position of Figs. 2 and 3 by pulling upwardly upon the ears 11 of the 25 slides 10. Similarly, to prevent air or rain from passing through the openwork band 5 and chilling the wearer's head, it is simply necessary to lower the band 15 to the position disclosed in Figs. 4 and 6.

30 As excellent results may be obtainable from the details disclosed, they may well be followed, but within the scope of the invention as claimed, numerous modifications may be made and obviously any or all parts 35 of the hat may be decorated in any desired manner. Also, a suitable lining, either ornamental or of other nature, may be provided, as will be readily understood.

It may be added that the lower edge portion 40 of the wall 3 is preferably pressed or

flattened to some extent to slightly decrease its thickness, so that when the wire or the like 5 is applied, it will be flush with the outer side of said wall.

We claim:—

1. A hat comprising a rim, an upper crown section having its side wall spaced above said rim, a lower crown section of openwork form connecting the rim with the upper crown section, vertical guides at the 45 inside of the hat connected with the rim and the upper crown section to hold them in properly spaced relation, slides movable vertically along said guides, and a band within the hat secured to said slides, said band being upwardly movable into the upper section 50 of the crown or downwardly movable for disposition at the inner side of said open-work lower crown section.

2. A structure as specified in claim 1; said band comprising upper and lower rings secured to said slides, and a strip of flexible material having its edges secured to said rings.

3. A structure as specified in claim 1; said 65 guides consisting of vertical plates having their edge walls bent inwardly toward each other to form channels, said slides consisting of vertical plates slidably engaged with said inturned edge walls and having inwardly directed ears at their upper ends.

4. A structure as specified in claim 1; said 70 guides and slides having co-acting means for holding the latter in either raised or lowered position.

In testimony whereof we have hereunto affixed our signatures.

STANLEY FRITZ.
ALEXANDER FRITZ.
